US0D1098487S

(12) **United States Design Patent** (10) Patent No.: **US D1,098,487 S**
(45) Date of Patent: ** Oct. 14, 2025

(54) **CARTRIDGE FOR MANIPULATING REAGENT DROPLETS**

(71) Applicant: **Nuclera Ltd**, Cambridge (GB)

(72) Inventors: **Saeed Fathi**, Cambridge (GB); **Kelvin Leung**, Cambridge (GB)

(73) Assignee: **NUCLERA LTD**, Cambridge (GB)

(**) Term: **15 Years**

(21) Appl. No.: **35/520,533**

(22) Filed: **Dec. 6, 2023**

(80) **Hague Agreement Data**

Int. Filing Date: **Dec. 6, 2023**

Int. Reg. No.: **DM/236214**

Int. Reg. Date: **Dec. 6, 2023**

(57) **CLAIM**

The ornamental design for a cartridge for manipulating reagent droplets as shown and described.

DESCRIPTION

Figure 1.1 is a front perspective view of a cartridge for manipulating reagent droplets showing my new design; Figure 1.2 is another front perspective view thereof; Figure 1.3 is a left side view thereof; Figure 1.4 is a right side view thereof; Figure 1.5 is a front view thereof; Figure 1.6 is a rear view thereof; Figure 1.7 is a top view thereof; and Figure 1.8 is a bottom view thereof.

(Continued)

The broken lines depict portions of the cartridge for manipulating reagent droplets that form no part of the claimed design.
